Attorney

UNITED STATES PATENT OFFICE.

CHARLES F. YOCUM, OF FINDLAY, OHIO, ASSIGNOR TO THE BUCKEYE TRACTION DITCHER COMPANY, OF FINDLAY, OHIO, A CORPORATION OF OHIO.

ROOTER-TOOTH ATTACHMENT FOR EXCAVATING BUCKETS.

Application filed July 9, 1924. Serial No. 725,008.

To all whom it may concern:

Be it known that I, CHARLES F. YOCUM, a citizen of the United States, and a resident of Findlay, in the county of Hancock 5 and State of Ohio, have invented a new and useful Rooter-Tooth Attachment for Excavating Buckets, which invention is fully set forth in the following specification.

This invention relates to buckets used in 10 connection with excavating machines, and has particular reference to a rooter attachment therefor.

The object of the invention is the provision of a rooter attachment of the class 15 described, which is strong and durable in its construction, capable of being easily attached to a bucket, and has a cutting tooth adapted to be used with one end as a cutting edge, and when such edge has become 20 worn to be then reversed to use the other end as a cutting edge.

The invention is fully described in the following specification, and while in its broader aspect it is capable of embodiment 25 in numerous forms, a preferred embodiment thereof is illustrated in the accompanying drawings, in which,

Figure 1 is a side elevation of a bucket embodying the invention with an associated 30 carrying chain. Fig. 2 is a front elevation of one end portion thereof, and Figs. 3 and 4 are enlarged side and top plan views of a rooter tooth holder embodying the invention.

Referring to the drawings, 1 designates 35 the nose plate of a bucket of the flat bottom type, which plate is formed with a front beveled cutting edge 2 and may be of any desired length to suit the width of the trench to be dug. The plate 1 is secured at each end to a bracket 3 attached 40 to a carrying chain 4 at the respective end of the bucket. A plate 5 is attached to and projects rearwardly from the rear edge 45 of the nose plate 1, and, in the present instance, is curved to project up between the carrying chains 4.

The rooter attachments embodying the invention comprise a plurality of tooth-holders 6, which are substantially U-form 50 or slotted to adapt them to straddle and closely fit over the forward edge portion of

the nose plate 1 of the bucket and to be rigidly secured thereto by rivets, bolts or other suitable securing means 7, which are 55 projected through registering apertures in the plate 1 and leg portions of the holder. The upper leg 8 of the holder is preferably shorter than the lower leg 9, but is of sufficient length to project a short distance 60 rearwardly over the front edge portion of the plate and to receive one of the securing members 7. The bottom of the recess 10 formed by the U-shaped portion of the holder is preferably beveled to adapt it 65 to correspond to and fit against the bevel 2 of the nose plate.

The outer end of each holder 6 is provided with a recess or socket 11, which is disposed longitudinally of the holder and extends to the bottom of the recess 10 and is beveled at its inner end to correspond to the bevel of said recess. The socket 11 is preferably of rectangular form in cross-section with its opposing sides parallel, and 70 is adapted to receive a rooter tooth 12, which is of greater length than the socket to adapt its forward end to project a distance therefrom and is adapted to fit in the socket to prevent lateral play. Each tooth 75 12, in the present instance, is of rhomboidal form, with the bevel of its ends corresponding to the bevel 2 of the nose plate so that either end of the tooth may be inserted into the socket 11 of a holder 6 and placed 80 in flat end-thrust engagement with the beveled cutting edge of the nose plate. The side holders of the socket 11 of the holder are each provided with an aperture 13 adapted to register with a central aperture 90 through the tooth for receiving a rivet 14 or other suitable securing means whereby a tooth may be firmly held in engagement with the holder. The aperture 13 is oblong to allow for tooth wear when reversed. 95

It is evident that any desired number of tooth-holders 6 may be provided along the front edge of a bucket nose plate 1, and that the teeth 12, when their outer beveled digging ends become worn, may be reversed 100 in the holders so that the other ends of the teeth may be employed as the outer cutting ends thereof, it being merely necessary to remove the rivets or other securing

means 14 to reverse the teeth and then to re-rivet or secure the teeth in the holders. This materially prolongs the life of the teeth without replacing, and enables the teeth to 5 be easily reversed when they become worn at one end.

I wish it understood that my invention is not limited to any specific construction, arrangement or form of the parts, or to 10 use in connection with any particular style of bucket, as it is capable of numerous modifications and changes without departing from the spirit of the claims.

Having thus described my invention, 15 what I claim as new and desire to secure by Letters Patent is:

1. The combination with an excavating bucket, of socketed rooter teeth holders attached to the nose plate of the bucket, and 20 rooter teeth of rhomboidal form removably and reversibly mounted in the sockets of said holders and in inner end-thrust engagement with the nose plate edge.

2. The combination with an excavating 25 bucket, of socketed rooter teeth holders attached to the nose plate of the bucket, and rooter teeth mounted in said holder sockets in inner end-thrust engagement with the cutting edge of the bucket nose plate.

3. The combination with the nose plate 30 of an excavating bucket, of individual rooter teeth holders secured to the nose plate in straddling engagement therewith and having their outer ends longitudinally socketed, and rooter teeth of rhomboidal form reversibly mounted in the holder sockets to adapt 35 either end thereof to be used as a cutting end and the other to bear against the cutting edge of the nose plate.

4. The combination with an excavating 40 bucket having a nose plate with a beveled cutting edge, of rooter teeth holders mounted on and projecting from the cutting edge of the nose plate, and having their outer ends longitudinally socketed, and 45 rooter teeth reversibly mounted in the holder sockets and having their ends beveled in parallel relation to adapt either to be placed in parallel abutment with the beveled cutting edge of the nose plate and the other 50 to form a cutting edge.

5. In an excavating bucket, a rooter tooth holder having a socket therein attached to the nose plate of the bucket, a reversible rooter tooth of substantially rhomboidal 55 form in said socket having its inner end in thrust engagement with the edge of the nose plate, and means extending through said tooth for removably connecting the tooth to the holder, said means constituting the 60 sole securing means therefor.

6. In an excavating bucket, a rooter tooth holder having a socket therein attached to the nose plate of the bucket, a reversible rooter tooth of substantially rhomboidal 65 form in said socket having its inner end in thrust engagement with the edge of the nose plate, the upper and lower surfaces of said tooth lying in a plane approximately parallel to the longitudinal plane of the 70 holder, and means extending through said tooth for removably connecting the tooth to the holder.

In testimony whereof, I have hereunto signed my name to this specification.

CHARLES F. YOCUM.
